UNITED STATES PATENT OFFICE.

FREDERICK W. RIEDLER, OF THURSTON, NEBRASKA.

DRAFT ATTACHMENT.

SPECIFICATION forming part of Letters Patent No. 727,447, dated May 5, 1903.

Application filed October 18, 1902. Serial No. 127,792. (No model.)

To all whom it may concern:

Be it known that I, FREDERICK W. RIEDLER, a citizen of the United States, residing at Thurston, in the county of Thurston and State 5 of Nebraska, have invented certain new and useful Improvements in Draft Attachments; and I do hereby declare the following to be a full, clear, and exact description of the invention, such as will enable others skilled in the 10 art to which it appertains to make and use the same.

This invention relates to draft attachments for grain-separators or threshing-machines; and it consists in the novel construction and 15 combination of the parts hereinafter fully described and claimed.

In the drawings, Figure 1 is a plan view of a traction-engine, a tender, and a threshing-machine connected together according to this 20 invention. Fig. 2 is a detail side view of the foot-lever on the engine. Fig. 3 is a detail plan view of the coupling between the tender and the threshing-machine, showing the parts disconnected. Fig. 4 is a side view of the 25 parts shown in Fig. 3.

A is a traction-engine of any approved construction.

B is the tender for holding the fuel and water for the engine. This tender is connected to the engine by any approved coupling b.

C is a threshing-machine, grain-separator, or any agricultural implement or vehicle which may be drawn along at the rear of the 35 tender. This machine or load is provided with a draft-tongue c, having a forked end portion d and a vertical pin e.

D is a draw-bar secured at the rear of the tender B and provided with a forked end portion f, which has V-shaped guide-notches g at its end.

E is a bell-crank lever pivoted on a pin h in the forked end portion f and working in a horizontal plane. This bell-crank lever is 45 provided with a hook i, which has an inclined front portion j, and this hook works between the said guide-notches.

F is a spring which normally holds the hook in line with the draw-bar.

50 G is a foot-lever pivoted to the driving-platform a of the traction-engine, and H is a wire or other equivalent flexible connection

attached at one end to the said foot-lever and at the other end to the cross-arm h' of the said bell-crank lever.

55

The forked end portion d of the draft-tongue of the threshing-machine preferably consists of two plates, of which the upper plate 2 is longer and broader than the lower plate 3, so that it may have a large wearing-surface to bear on the top of the draw-bar, and both plates have beveled portions 4, so that they may slide easily into engagement with the draw-bar.

60

The threshing-machine is coupled automatically to the tender by pushing the parts of the coupling into engagement with each other. The uncoupling of the threshing-machine is effected from the engine by depressing the foot-lever. This is a great advantage, as 65 it enables the engine to start off at once when required without the threshing-machine or other load, which sometimes is highly necessary, as well as convenient. The coupling b between the engine and its tender is such as 70 to form a flexible connection between them and to permit them to turn corners.

What I claim is—

1. The combination, with a traction-engine, a wheeled tender independent of the said engine, and a draft-coupling between the said engine and tender; of a draw-bar secured to the tender and provided with a coupling for the load, an operating device carried by the engine, and a flexible connection between the 85 said operating device and coupling, substantially as set forth.

80

2. The combination, with a traction-engine, a wheeled tender independent of the said engine, and a draft-coupling between the said engine and tender; of a draw-bar secured to the tender and provided with a forked end portion having guide-notches at its end, a bell-crank lever provided with a hook for engaging the load and pivoted in the said forked 90 end portion, an operating device carried by the said engine, and a flexible connection between the said operating device and the cross-arm of the said bell-crank lever, substantially as set forth.

95

3. The combination, with a traction-engine, and its tender; of a draw-bar secured to the tender and provided with a coupling, a draft-tongue provided with a vertical pin and 100

plates which have beveled portions and which straddle the said coupling, the upper of the said plates being longer and broader than the lower, an operating device carried by the engine, and a flexible connection between the said operating device and coupling, substantially as set forth.

In testimony whereof I affix my signature in presence of two witnesses.

FRED. W. RIEDLER.
